COMBINED TRAY AND LIGHT HOUSING

Ralph F. Chambers, Decatur, Ga., assignor to Gladwin
Plastics, Inc., Atlanta, Ga., a corporation of Georgia

Filed May 3, 1960, Ser. No. 60,431

Term of patent 14 years

(Cl. D80—11)

FIG. 1

FIG. 2

FIG. 3

FIG. 4

FIG. 5

FIG. 1 is a perspective view taken from a front corner of a combined tray and light housing embodying my new design;

FIG. 2 is another perspective view thereof taken from the right rear corner shown in FIG. 1;

FIG. 3 is a top plan view thereof;

FIG. 4 is a side elevation view thereof; and

FIG. 5 is an end elevation view thereof.

I claim:

The ornamental design for a combined tray and light housing, substantially as shown.
